UNITED STATES PATENT OFFICE.

PETER H. SEREFF, OF LIMA, OHIO.

REINFORCED SUPPORTING MEMBER.

Application filed May 12, 1926. Serial No. 106,643.

In the construction of buildings it has frequently been found necessary to forego fireproof concrete structures; not because of the expense of the material itself, but because of the great expense involved in time, labor and material necessary in the erection of the temporary centering and form work and in the fabrication of the different materials entering into its erection. It has been estimated that this expense alone amounts to 40% of the entire cost of construction. An object of the present invention therefore resides in the provision of a fabricated reenforced supporting member with self-sustaining features whereby the weight of the green concrete will be maintained without the use of external supports heretofore employed.

A further object of the invention resides in the provision of a bottom chord or soffit form, temporary or otherwise, for supporting the metal core form used in the construction.

Another object of the invention consists in the use of reinforcing steel rods which serve to suspend the weight of the green concrete while setting.

Other objects and advantages of the invention will be apparent from the following description when taken in connection with the accompanying drawings; in which,

Figure 1 is a side elevation of the assembled reenforced supporting member.

Figure 2 is an enlarged fragmentary view thereof.

Figure 3 is a vertical section through one end of the reenforced supporting member and shear plate.

Figure 4 is a fragmentary elevational view of one of the two sections forming the main body of each supporting member.

Figure 5 is a section taken on line 5—5 of Figure 4.

Figure 6 is a fragmentary sectional view through a concrete floor showing the supporting members imbedded in the concrete.

Figure 7 is a perspective view, partly broken away, of an expansion rod used in the construction.

Figure 8 is a fragmentary side elevation of a modified form of the invention.

Figure 9 is a vertical section through the reenforcing member shown in Figure 8; and

Figure 10 is a detail perspective view showing the supporting means for the soffit form.

I will now describe in detail the several elements of both the preferred and modified forms of the invention; similar reference numerals indicating corresponding parts in the several views.

Referring to that form of the invention shown in Figures 1 to 7 inclusive, the numeral 1 indicates generally the metal reenforced supporting member which is composed of two frame members 2 placed back to back and permanently secured together by welding or any other preferred manner. Each of these frame members 2 is of substantially rectangular outline and is provided at its upper edge with the channel formation 3 and its lower edge with the channel formation 4. These lower channel members 4 of the two frame members combine to provide a horizontal base portion on which the core forms to be later described are mounted.

Between the upper and lower channel formations 3 and 4 the frame members are provided with inclined braces 5 preferably integrally formed therewith and semicircular in cross section. These braces are arranged in parallel relation in each frame member and when the latter are placed back to back as shown in Figures 3 and 6 the braces coact to form a zigzag formation as disclosed in Fig. 1.

In securing the frame members 2 in their back to back relation shear plates 6 are inserted between the frame members at each end thereof to strengthen and reenforce the same. Also secured at each upper end of each frame member is a reenforcing rod 7 provided with an intermediate looped portion 8 which extends parallel and adjacent to the horizontal base portion composed of the channel members 4. This looped portion 8 of the reenforcing rod 7 passes under hooks 8' which are anchored to the frame members 2 and thereby function to transmit the load on the horizontal base portion of the reenforcing member to the upper portion thereof.

The flanges 9 of the horizontal base portion or the channel members 4 which compose this portion, are provided with struck

out tongues 10 between which and the flanges 9 are received the lower edges of the core forms 11 as more clearly shown in Figure 6.

These core forms 11 extend from one reinforcing member to the next adjacent reinforcing member and in order that these reenforcing members may be properly spaced I have provided spacing rods 12 (Fig. 7) which are provided with down turned fingers 13 adapted to be inserted in the spaces between the upper channel portions 3 of the frame members 2.

In Figure 6 a section of a floor or ceiling is shown disclosing two of the reenforced supporting members and the spacing member 12 in cooperation therewith. In this figure the concrete has been poured into the forms and the expanded metal or the like 14 attached to the horizontal base portion and the plaster applied thereto in the usual manner. The method of applying the plaster or of applying the floor structure to the upper portion of the concrete formation forms no part of the present invention and therefore need not be described in detail.

In Figures 8, 9 and 10 of the drawing I have shown a slightly modified reenforced supporting member for concrete constructions but which nevertheless is also composed mainly of two metallic frame members 20 provided with upper channel members 21 and lower flanges 22. These frame members are also placed back to back and permanently secured by welding or otherwise, and are provided with angularly disposed braces 23 of substantially semicircular cross section. This form of the invention also is provided with shear plates 24 disposed at each end of the reenforced supporting members and interposed between the frame members 20.

A reenforcing rod 25 is permanently secured at each end to the respective ends of each channel portion 21 of the frame members and is provided with a looped portion 26 which extends parallel with and adjacent to the bottom edge of the frame member. Anchored to the bottom portion of the frame member are a plurality of hooks 27 which engage over this looped portion 26 of the reenforcing rod 25 and which serve to transmit the load on the lower portion of the reenforced supporting member to the upper portion thereof. The construction thus far described in connection with Figures 8, 9 and 10 is identical with that previously described in connection with Figures 1 to 7 inclusive except for the flanges 22. In the present modified form of the invention the frame members 20 instead of being provided with lower channel portions extending throughout their length are provided with relatively short channel portions or soffit forms 28 permanently secured at each end of the frame members and these portions are provided with struck out tongues 29 identical

with the tongues 10 previously described. In lieu of having these channel portions extending throughout the length of the frame member I provide a suspended soffit form which may be composed of a plurality of sections of random lengths adapted to be removed after the concrete is poured and sets. These removable soffit forms are indicated by numeral 30 and are shown in dotted lines (Fig. 8) as suspended below the channel formations 28.

These forms are suspended by means of wires 31 which are passed over the looped portion 26 of the reenforcing rod 25 and have their ends extended through apertures formed in the base of the soffit forms. These wires are then twisted as indicated by numeral 32 in Fig. 8 so as to draw the soffit forms up into substantial alignment with the channel portions 28 of the frame members 20. The core forms 11 are supported between the flanges of the channel members 28 and the tongues 29 struck therefrom in the same manner as previously described, and the spacing rods 12 will have their down turned fingers 13 disposed between the edges of the channel members 21 as previously described in connection with the disclosure of Figures 1 to 7 inclusive.

This present form of the invention has the advantage over the first-described form in that after the concrete is poured in the usual way the soffit forms 30 which are composed of a plurality of relatively short sections may be removed after untwisting or clipping off the ends of the wire 31 and may be used on other constructions. The ends of the wires 31 may then serve to support metal lathing or the like for the reception of the plastered ceiling.

In operation, the reinforced supporting members are arranged in parallel relation, properly spaced apart, and the spacing or expansion rods 12 are then placed at each of the supporting members to hold them in position until the floor cores are placed. The floor cores 11 are then placed in position with their lower edges supported between the flanges 9 and tongues 10 of the horizontal base portion. Suitable end closures for the floor cores may be employed, and intermediate spacing rods are placed at intervals so as to tie the supporting members together. The concrete is now poured and produces the integral joists and floor slab shown in Figure 6. After the concrete hardens the forms are quickly removed and can be used again if desired, or permanent forms may be employed. Metal lath may now be secured to the bottom of the joists and plastered in the usual manner.

In the modified form of the invention the soffit forms 30 may also be removed and reused; and the metal lathing attached to the wires 31.

From the foregoing description taken in connection with the accompanying drawings it will be apparent that I have devised a strong and durable reenforced supporting member for concrete forms which requires no exterior supports or props as in the constructions heretofore known, and in which the weight of the green concrete is transmitted to those portions of the reinforced supporting members most able to carry the same, by means of the reenforcing rods hereinbefore described.

In accordance with the patent statutes I have described what I now believe to be the best embodiment of the invention, but I do not wish to be understood thereby as limiting myself or the scope of the invention, as many changes and modifications may be made without departing from the spirit of the invention; all such I aim to include in the scope of the appended claims.

What I claim as new and desire to secure by Letters Patent is:

1. In a concrete floor or the like, a metal reenforced supporting member including a horizontal base portion, flanges on said base portion, and tongues struck-up from said flanges, whereby the edges of core forms may be mounted between said flanges and their respective tongues.

2. In a concrete floor or the like, a metal reenforced supporting member including a horizontal base portion, flanges on said base portion, tongues struck-up from said flanges, and core forms supported on said base portion with their edges engaged between said flanges and tongues.

3. In a concrete floor or the like, a metal reenforced supporting member composed of a pair of skeleton frames arranged back to back and secured together, overhanging flanges at the top of said frames, a horizontal base portion formed on the bottom of said frames, and reenforcing rods having their ends secured to said overhanging flanges and their intermediate portions secured to said horizontal base portion.

4. In a concrete floor or the like, metal reenforced supporting members each composed of a pair of frames arranged back to back, horizontally spaced, overhanging flanges on each pair of frames, and an expansion rod having downturned ends adapted to be inserted between said horizontally spaced flanges.

5. In a concrete floor or the like, an elongated metal reenforced supporting member, base members permanently secured to the reenforcing member at the ends thereof, a reenforcing rod having its ends secured to said member and providing an intermediate loop, soffit forms adapted to form continuations of said base members, and means for detachably suspending said soffit forms from said reenforcing rod.

6. In a concrete floor or the like, a metal reenforced supporting member, a reenforcing rod having its ends secured to said member and provided with an intermediate loop, a soffit form provided with apertures, and wires engaged over said loop portion of the reenforcing rod and having their ends passed through said apertures and secured.

PETER H. SEREFF.
